UNITED STATES PATENT OFFICE.

JOHN C. WELLER, OF CHICAGO, ILLINOIS, ASSIGNOR TO HARRY C. FARWELL, OF SAME PLACE.

WINDOW.

SPECIFICATION forming part of Letters Patent No. 681,008, dated August 20, 1901.

Application filed March 25, 1901. Serial No. 52,771. (No model.)

To all whom it may concern:

Be it known that I, JOHN C. WELLER, a citizen of the United States, residing at Chicago, in the county of Cook and State of Illinois, 5 have invented certain new and useful Improvements in Windows; and I do hereby declare the following to be a full, clear, and exact description of the invention, such as will enable others skilled in the art to which it applies to make and use the same.

My invention relates to a novel construction in a window wherein the sashes and frames are made principally of sheet metal, the object being to produce a window which will be 15 fire, wind, and weather proof and in which the sashes can be easily operated; and it consists in the features of construction and combinations of parts hereinafter fully described and claimed.

20 In the accompanying drawings, illustrating my invention, Figure 1 is an inside elevation, partly in section, of a window made in accordance with my invention. Fig. 2 is a vertical section on line 2 2 of Fig. 1. Fig. 3 is 25 an enlarged horizontal section on line 3 3 of Fig. 2. Fig. 4 is a partial section on line 4 4 of Fig. 3.

My window consists of the frame 1, provided with grooves 2 and 3, in which the sashes 30 4 and 5 move, the latter being counterbalanced by the sash-weights 6 in the usual manner. Said sashes 4 and 5 comprise the frames 7, which are narrower than the opening in said frame 1 and are horizontally pivotally mounted on members 8, which are adapted to fill the space between the lateral edges of 35 said frames 7 and the bottoms of said grooves 2 and 3. The lateral edges of said sash-frames 7 are channel-shaped, whereby a space 40 9 is provided between the members 8 and the body of said sash, which space is adapted to be filled with a resilient fireproof packing 10. Said packing 10 acts not only to prevent the passage of air through the joint between said 45 frames 7 and the members 8, but also to hold said frames and members laterally with a yielding pressure. Said members 8 are channel-shaped, having the channel turned toward said frame 1, and are provided with 50 lateral projecting flanges 11, which are adapt-

ed to cover the joint between said frames 7 and members 8, said flanges being cut away above and below the middle portion of said sash on opposite sides in order to permit the sash to be swung on the pivots 12 to assume 55 a position as indicated in dotted lines in Fig. 2. Said frames 7 are secured in their vertical positions by means of the latches 13, comprising arms which are pivotally mounted on the inner sides of said frames 7 and engage hooks 60 on the adjacent flanges 11 of the members 8. Said members 8 are thickened where the pivots 12 pass through the same by means of the block 14, which is firmly riveted to said members 8. The upper end of said block 14 is 65 provided with a recess 15 and a vertical opening 16, in and through which the weight-cord 17 is secured.

In order to be able to get at the balance-weights 6, openings 18 are provided in the 70 frame 1 in the bottom of said grooves 2 and 3, which are adapted to be closed by means of the slides 19. Said slides 19 are fitted to the contour of the inner surface of the frame 1 and are held in place by means of the guides 75 20, which are secured to said frame 1. Said slides are provided with a lifting-notch 21 near their lower ends.

The guide-grooves 2 and 3 are partly formed by the frame 1 and partly by removable 80 spring-stops 22 and 23. Said stops are U-shaped in cross-section, their free edges being adapted to enter vertical grooves in said frame 1. They are adapted to be held in place by means of the screws 24, thickening-blocks 25 being provided, riveted to said frame 1, into which said screws are adapted to be threaded. The groove in which said stop 22 is placed is narrower than the outer part of 85 said stop, so that the outer part of said stop overlaps the joints at the edge of said groove, thus giving a finished appearance to the outer joint and at the same time preventing the edge of said member 8 from entering the inner joint. Said stop or parting-strip 23 has 90 parallel sides, the member 8 being prevented from entering the joint by bearing on said frame 1 at its opposite edge. Said members 8 22 23 and the part of the frame 1 forming the 95 other wall of the groove 2 are relatively so 100

made that when in proper relative position they will crowd each other, and owing to the fact that all of said parts are hollow and made of sheet metal they will yield sufficiently to prevent jamming, there being a certain amount of inherent elasticity in the metal which I take advantage of to keep said parts always pressing against each other. The degree of lateral movement imparted to 10 said members at any time is necessarily so slight as to be incapable of illustration. A vertical projecting flange 27 is formed in the center of the lateral and side edges of said frame 1, which is adapted to hold said frame 15 in the wall into which it is built and at the same time form a break in the joint between said frame and wall. The meeting-rails of said sashes 4 and 5 are provided with horizontal flanges 28 on their upper and lower 20 edges, respectively, adapted to close the space between said sashes and said parting-strip 22. Said lower sash 5 is provided with an outwardly-projecting horizontal flange 29 on its lower edge, adapted to fit closely to the sill 25 30 of said frame 1 when said sash is in its normal closed position in order to make the joint between said sash and sill weatherproof.

I claim as my invention—

- 30 1. In a window, the combination with a frame provided with guide-grooves bordered by yielding stops of shoes movable in said grooves, and sashes mounted on said shoes, said yielding stops being adapted normally to press against said shoes to form weatherproof joints.
2. In a window, the combination with a frame provided with grooves having yielding side walls adapted to normally contract said 40 grooves in width at their mouths, of sashes movable in said guide-grooves, said sashes being adapted to force said yielding walls outwardly to form weatherproof joints between said frame and said sashes.
- 45 3. In a window, the combination with a frame and sashes movable therein, of yielding guide-strips on said frame engaging said sashes and guiding same, said guide-strips being adapted to normally press against said

sashes to form weather-tight joints between 50 said frame and said sashes.

4. In a window, the combination with a frame provided with guide-grooves, shoes movable in said guide-grooves, sashes pivotally mounted on said shoes, and means for locking said sashes rigid with said shoes, of yielding strips bordering said guide-grooves and normally pressing against the sides of said shoes to form weather-tight joints, and packing between said shoes and said sashes 60 to form weather-tight joints.

5. In a window, the combination with a frame provided with guide-grooves, of shoes movable in said guide-grooves, sashes mounted on said shoes, said sashes and shoes being 65 capable of lateral movement with relation to each other, and a packing of yielding material interposed between said sashes and said shoes for forcing the latter laterally outward with relation to said sashes, thereby forcing 70 said shoes into said guide-grooves.

6. In a window, the combination with a frame provided with guide-grooves, of shoes movable in said guide-grooves, sashes pivotally mounted on said shoes, said sashes and 75 shoes being laterally movable with relation to each other, and a packing of yielding material interposed between said sashes and said shoes for forcing the latter laterally outward with relation to said sashes, thereby forcing 80 said shoes into said guide-grooves.

7. In a window, the combination with a frame provided with guide-grooves, of shoes movable in said guide-grooves, sashes pivotally mounted on said shoes, said sashes and 85 shoes being laterally movable with relation to each other, and a packing of yielding material carried by said sashes and engaging said shoes to form a weather-tight joint between the same, said packing being adapted to force 90 said shoes laterally outward with relation to said sashes and into said grooves.

In testimony whereof I affix my signature in presence of two witnesses.

JOHN C. WELLER.
